UNITED STATES PATENT OFFICE.

FRED J. KLINE, OF NEW YORK, N. Y.

PAPER-FILING DEVICE.

Application filed June 28, 1924. Serial No. 722,892.

This invention relates to paper filing devices and particularly to devices for filing letters, vouchers, documents and the like.

The main object of the invention is to provide a paper filing device that is especially adapted for filing small numbers of letters, vouchers, documents and the like. Another object is to provide a device of this type which is simple in operation and low in cost 10 of manufacture.

The means I prefer to employ for effecting the above-named objects, are illustrated in the accompanying drawing which forms part of this specification, and in which—

15 Figure 1 is a perspective view of one form of my improved paper filing device.

Fig. 2 is a perspective view of a paper fastener for use in my invention.

Like characters of reference refer to like 20 parts in all the figures of the drawing.

Referring to Fig. 1 of the drawing, the numeral 1 denotes the backing member of a paper file. Ordinarily the said backing member forms one of a pair of folding covers 1 25 and 2, and which covers are preferably connected together in any suitable way, as in this instance directly, along the folding line 3.

On the backing member or cover 1 is a 30 member which I term the flap and is denoted by the numeral 4. The flap has a free or movable portion 4^a and a portion 4^b attached preferably by pasting to the backing member or cover 1 near its left hand part or adjacent 35 to the folding line 3. I provide slits 5 in the free portion 4^a of the flap 4, and each of said slits in this form of the device consists of two parts, first a part 5^a starting at the outer edge of the free portion 4^a, oblique thereto and joined to a second part 5^b parallel to the ends of the flap.

40 Preferably I place a paper fastener such as 7 of Fig. 2, in the said slits 5, and said fasteners ordinarily consist of a main portion 8 and two spaced apart tongues 9 which can be bent up at right angles to the portion 8. To place the paper fastener 7 on the flap 4, the portions 10 of the flap, adjacent to the slits 5 are bent upwardly and the fast-

50 eners 7 with their tongues 9 at right angles to their main portions are pushed laterally into the parts 5^b of the slits 5, and on releasing the portions 10, the said fasteners are held on the flap 4 by frictional contact with the slits 5. Papers to be filed are perforated 55 and pushed onto the tongues 9 and these are then bent neatly down on the papers.

The foregoing paper filing device is intended for use especially where only a small 60 number of papers such as one to half a dozen or so, is desired to be filed, and the above-described device is particularly advantageous as its construction is simple and inexpensive.

What I claim is:—

1. The combination with the backing member of a paper file, of a flap secured to said backing member near one boundary thereof and having a movable portion and a pair of spaced apart slits therein adapted to hold a two tongued paper fastener by its tongues, 65 each slit having a portion substantially at right angles to said boundary of the backing member and a portion oblique thereto which last-mentioned portions are slanted away from each other toward the edge of 70 the movable portion, and a paper fastening device having spaced apart tongues registering with the first-mentioned portions of said slits and whereby it can be secured to said flap by passing said tongues laterally 75 into the slits on bending the portions next to the oblique parts of said slits and be held by the frictional contact of the edges of the slits on the fastener tongues.

2. The combination of a backing member 80 for a sheet-material file, and a flap secured by substantially one edge to said backing member, the free portion of said flap being provided with a plurality of perforations connected by slots with one of the free edges, 85 said slots being oblique to the edge so as to retain the prongs of a fastening element inserted in said perforations.

Signed at New York, in the county of New York, and State of New York, this 23d day 90 of June, 1924.

FRED J. KLINE.
